UNITED STATES PATENT OFFICE

ROY V. YEAGER, OF DES MOINES, IOWA

APPARATUS FOR FIREPROOFING STRUCTURAL METAL

Application filed February 7, 1928. Serial No. 252,526.

The object of my invention is to provide means of simple and inexpensive construction that may be readily, quickly and easily applied to metal building structures, such for instance as I-beams and I-columns, for the purpose of enabling the builder to readily, quickly and easily apply a fireproofing material to the structural metal members.

My invention consists in the construction, arrangement and combination of the various parts of the fireproofing material, whereby the objects contemplated are attained, as hereinafter more fully set forth, pointed out in my claims, and illustrated in the accompanying drawings, in which:

Figure 1 shows a perspective view of one of my improved spacing blocks and wedge lock devices.

Figure 2 shows a horizontal sectional view of a structural I-column having my improved fireproofing applied thereto as in use.

Figure 3 shows a vertical sectional view of an I-beam and a portion of a concrete floor supported thereby and having my improved fireproofing applied to the beam; and

Figure 4 shows a side elevation of a part of a structural metal I-column having my improved fireproofing device applied thereto, a portion of the fireproofing being broken away to illustrate the arrangement and location of the spacing blocks.

Referring to the accompanying drawings, I have used the reference numeral 10 to indicate a metal I-beam of ordinary construction.

My improved fireproofing apparatus comprises a series of spacing blocks which may be made of gypsum or the like, and indicated by the numeral 11. Each of these spacing blocks has in one corner, a tapered notch 12, and this notch is so shaped that one of its faces will lie flat against one end of the I-beam to which it is applied, as shown in Figure 2, and the other face of the notch will stand at an obtuse angle relative to the first mentioned face of the notch, as shown in Figure 2.

For securing this spacing block to the column, I have provided a wedge shaped locking device indicated by the numeral 13, and this locking device has formed integral

with it a rib 14. In use the builder places a coating of plaster or the like on both side edges of the wedge 13, and he then inserts the wedge into the notch 12 of the block 11, with one face engaging the block 11 and the other engaging the adjacent portion of the I-beam flange, as shown in Figure 2, and hence as soon as the plaster has set and hardened, the spacing block will be firmly supported in position.

I apply a series of the spacing blocks 11 to all four edges of the flanges of the column in positions spaced apart from each other as shown in Figure 4. I then take sheets of plaster board 15 and place them in position resting upon the ribs 14 of the adjacent spacing blocks, as shown in Figure 2. I temporarily support these plaster boards in position by small portions of cement 16 which may be applied at intervals throughout the height of the plaster board, and which form a bond between the adjacent surfaces of the plaster board and the spacing blocks. I then apply sheets of plaster board 17 to the outer surfaces of the spacing blocks, forming a rectangular figure and completely enclosing the column and the spacing blocks. I then pour plastic material, such as gypsum, in the spaces between the plaster board 15 and the adjacent plaster board 17, and also between the plaster board 17 and the adjacent ends of the column. This plastic material will completely fill the said spaces and also the spaces between the spacing blocks 11, and when set and hardened will become bonded with each other, and will thereby firmly and permanently support the spacing blocks in their proper positions, and also support the plaster boards 15 in their proper positions, and the plaster boards 17 will be thoroughly bonded to the plastic material which has been poured in the spaces.

When the fireproofing has been applied in this manner, then there is around the column a monolithic fireproofing structure of, say for instance, two inches in thickness, and the spaces between the web of the beam and the plaster boards 15 become dead air spaces, which of themselves perform fireproofing functions and the expense of the fireproofing

material for filling these dead air spaces is saved.

When the fireproofing is to be applied to a structural I-beam, then the method before described is employed throughout, except that the plaster board at the upper end is omitted, and the concrete floor 18 is laid directly upon the top of the beam, forming a fireproofing structure for the upper surface of the beam. When my improved fireproofing method is used for beams that extend horizontally, the plastic material is poured in through the top after the spacing blocks and plaster boards have been applied to the bottom and sides of the beam.

The outer plaster board layers may be temporarily held in position before the plastic material is poured between them either by temporarily tacking them to the spacing blocks 14, or by putting a band around the entire column, which later may be removed.

With my improved apparatus, a column may be adequately fireproofed with a minimum of labor and in a relatively short time, because all that the operator does is to take the precast spacing blocks and wedges and dip the wedges in plaster and then place the blocks at spaced intervals throughout the length of the column and put the wedges in position. The plaster will cause an initial adhesion sufficient to hold the spacing blocks in position until the plaster has set and hardened, and when that takes place the blocks are held quite firmly. The builder then cuts the plaster boards 15 to proper widths and simply places them in position resting against the ribs 14 and temporarily supports these plaster boards 15 in position by small particles of plaster applied at spaced intervals to the plaster board and the spacing blocks. Then the four outer sheets of plaster board are placed in position and temporarily held either by tacking through them into the spacing blocks, or by tying a wire around all four of them. Then the plastic material, such as gypsum, is poured in from the top to completely fill the spaces between the spacing blocks and plaster board.

I claim as my invention:

1. A fireproofing apparatus for structural metal, comprising a series of spacing blocks made of fireproofing material, each formed with a V-shaped notch in one edge, a V-shaped wedge for each spacing block having a rib projected outwardly from it, said wedge being designed to receive a coating of plaster and to be placed in the wedge shaped notch and to be held in such position by the bonding action of said plaster, plaster board sheets shaped to rest against the said ribs of the wedges and to lie parallel with, and spaced apart from, the web of the structural metal, a series of plaster board sheets placed against the outer surfaces of the spacing blocks and completely encircling the

structural metal, and plastic material inserted in the spaces between the plaster boards that engage the ribs of the spacing blocks and the outer plaster boards at the sides of the structural metal, and also the spaces between the ends of the structural metal webs and the plaster board at the outside of the ends.

2. In a fireproofing apparatus for structural metal, the combination of a substantially rectangular spacing block made of plastic material and having a notch at one corner to receive the edge of the structural metal member, a wedge made of fireproofing material and shaped to enter said notch and to engage one side of the notch and the adjacent side of the structural metal, and being designed to receive layers of plaster to cause it to bond with the adjacent surfaces of the block and the structural metal.

3. In a fireproofing apparatus for structural metal, the combination of a substantially rectangular spacing block made of plastic material and having a notch at one corner to receive the edge of the structural metal member, a wedge made of fireproofing material and shaped to enter said notch and to engage one side of the notch and the adjacent side of the structural metal, and being designed to receive layers of plaster to cause it to bond with the adjacent surfaces of the block and the structural metal, and a rib projected outwardly from said wedge and designed to form a support for the layer of plaster board.

4. In a fireproofing apparatus for structural metal, the combination of a series of blocks, each having a notch to receive an edge of a structural metal member, means for temporarily fixing said blocks to the structural metal member, sheets of plaster board fixed to said blocks and surrounding the structural metal member and spaced apart from it by said blocks, and a body of plastic material between the plaster board sheets and bonded to the blocks and the structural metal to permanently connect all of said parts.

5. In a fireproofing apparatus for structural metal, the combination of a series of blocks, each having a notch to receive an edge of a structural metal member, means for temporarily fixing said blocks to the structural metal member, sheets of plaster board fixed to said blocks and surrounding the structural metal member and spaced apart from its web by said blocks, and lugs connected with said blocks to support plaster boards spaced from the web of the structural metal and also spaced apart from the plaster boards secured to the outer surfaces of the blocks.

Des Moines, Iowa, January 11, 1928.
